SEALING RING FOR ROTARY KILNS

Fred A. Mertz, Allentown, Pa., assignor to Traylor
Engineering & Manufacturing Company, Al-
lentown, Pa., a corporation of Delaware

Application December 30, 1948, Serial No. 68,320

10 Claims. (Cl. 285—97.6)

1

The invention of the present application is a modification of and improvement upon the sealing means shown, described, and claimed in my copending application Serial No. 706,439, filed October 29, 1946, entitled Sealing Ring for Rotary Kiln, now Patent No. 2,461,754, February 15, 1949.

As was the case with the invention of that application, the present invention relates to rotary kilns of the type used in the manufacture of Portland cement and the like. More particularly, the invention is concerned with improvements in the sealing means between the end of a rotary kiln and the normally stationary firing hood, positioned adjacent thereto.

In the past, various types of seals have been provided between the ends of rotary kilns and the adjacent firing hoods, but numerous difficulties and disadvantages have been encountered in their use. One of the most generally used constructions consists of a pair of flanged rings carried by the kiln and hood respectively, making a substantially running contact or spaced apart a predetermined distance, for the admission of currents of atmospheric air, tending to maintain the end of the kiln shell at reasonably cool temperatures, to prevent overheating and burning out of the same. In such constructions however, it has been necessary to advance and retract the firing hood with respect to the rotary kiln, to compensate for axial expansion and contraction of the latter under the influence of temperature changes. Even though the firing hood be mounted on track supported wheels, the adjustment of the hood and its associated parts is a laborious and troublesome operation. Moreover, difficulty is encountered in maintaining the space between the fixed and rotatable rings constant during the operation of the apparatus, and nicety of adjustment in this connection has been difficult or impossible to accomplish.

One of the primary objects of the present invention is to overcome the difficulties encountered in the use of prior art seals between the ends of rotary kilns and the adjacent stationary firing hood.

A further object is to provide a construction in which the hood need not be moved to compensate for expansion and contraction of the kiln, but in which the kiln is free to move axially, under the influence of temperature changes, relative to the firing hood.

A further object of the invention is to provide adjustable means for accurately determining the space between the fixed and movable parts of a seal for the end of a rotary kiln and associated

2

firing hood. A further object is to provide a construction in which the space between the stationary and rotatable parts will not vary during the operation of the apparatus, in the event of expansion or contraction of the kiln, resulting from temperature changes.

Another object of the invention is to provide a seal of the type described in which the parts are constantly maintained in the desired, closely fitting relation by the influence of gravity, working on one part and tending to move the same toward the other.

Another object is to provide long lasting, efficient, anti-friction connections between the fixed and movable parts, thereby reducing wear and other adverse factors.

Another object of the invention is to provide an improved seal, in which one sealing ring is non-rotatably supported by an enclosure, such as a firing hood or stack base, with capability of limited axial movement relative thereto, and in which a second, rotatable ring, encircling the end of the kiln and rigidly secured in gas-tight relation thereto, is disposed in sealing relation thereto.

Another object of the invention is to provide a seal comprising a radially projecting ring secured to the kiln for axial movement therewith, upon expansion and contraction of the kiln, and an axially movable, non-rotatable ring, disposed in sealing relation with respect to the first ring and having a gas-tight connection with the adjacent firing hood or other enclosure.

Another object of the invention is to provide a seal comprising a pair of sealing rings, one of which is rotatable and the other of which is stationary, in which anti-friction rollers are carried by the non-rotatable ring, and in which conduits for lubricating material deliver lubricant thereto from an external, fixed source.

Other and further objects and advantages of the invention will be apparent from the following description of a preferred embodiment, shown in the accompanying drawings, in which:

Figure 1 is a side elevation, with certain parts in section, of the lower end of a rotary kiln and an associated firing hood, having the improved seal incorporated therein;

Figure 2 is a section on line 2—2 of Figure 1;
Figure 3 is an enlarged section, taken on line 3—3 of Figure 2, and

Figure 4 is an enlarged elevation taken substantially on line 4—4 of Figure 2.

A rotary kiln having a metallic shell 10 may be supported for rotation about its longitudinal

axis, in inclined relation to the horizontal axis, by suitable means, well understood in the art, and therefore not shown in the accompanying drawings. A kiln of this type is conventionally lined with refractory brick work, not shown, and has its lower ends 11 projected into the open forward end 12 of a firing hood 13. The latter may be mounted upon wheels, for longitudinal movement toward and away from the kiln, as explained in the above mentioned application. Secured to the forward end of the shell of the firing hood, surrounding the circular opening therein, is a collar 14, having an inwardly extending flange 15 and a cylindrical flange 17, of downwardly increasing length, as indicated at 18, so that its forward edge is disposed on a plane perpendicular to the axis of the kiln 10.

The firing hood shell 13 carried a pair of brackets 19 and 20, having forwardly projecting arms 21 and 22, the upper surfaces of which are parallel to the axis of the rotary kiln and carry tracks 23, 24. A ring casting 25 having a cylindrical flange 26 and a radial flange 27 has formed integrally therewith a pair of diametrically projecting, hollow bosses 28 and 29, in which stub shafts are disposed, supporting wheels 30 and 31, riding on tracks 23 and 24, so that the ring casting as a whole is capable of limited longitudinal movement relative to the collar 14.

Encircling the flange 17 of the collar 14 is a rod 32, welded in place, and a similar rod 33 is similarly secured to the rear portion of the cylindrical flange 26 of ring casting 25. An annular strip 34 of flexible heat resisting material has its inner edge portion seated against the rod 32 and clamped upon the periphery of the flange 17 by a clamping wire 35. The outer edge of the flexible strip 34 is secured in gas-tight relation to the outer edge of a similar, inwardly projecting, annular strip 36 of flexible, heat-resisting material. The inner edge of the latter strip, likewise, is seated against the rod 33 and is clamped upon the periphery of the flange 26 of ring casting 25 by a clamping wire 37. Thus, the strips 34 and 36 constitute a gas-tight seal between the collar 14 and the ring casting 25, but permit axial movement of the ring casting relative to the hood. The strips may be made of thin flexible metal, but preferably are of asbestos cloth having a wire mesh inner layer.

A sectional ring casting 40, encircling the lower end of the kiln shell 10, having a plurality of terminal webs 41, by which the sections are interconnected, is welded to the shell, as indicated at 42 and 43 in Figure 3. The ring casting 40 carries a circumferentially continuous, forwardly facing, sealing ring 44, for rotation with the kiln, while the flange 27 of the non-rotatable ring casting 25 carries a rearwardly facing sealing ring 53 in juxtaposed relation thereto.

The outer or forward face of the radial flange 27 of the non-rotatable ring casting 25 is provided with a plurality of pairs of forwardly projecting blocks 45, 46, having arcuate seats therein for the reception of the reduced ends 47 of stub shafts, having eccentric body portions 48, upon which rollers 49 are journalled. The shafts may be secured in angularly adjusted relation by caps 50 and 51, as explained in the above mentioned application, to adjust the degree of projection of rollers 49 through the adjacent slots 52 and 54 in the flange 27 and ring 75

53, to control the spacing between the rings 44 and 53, and the amount of atmospheric air permitted to flow into the lower end of the kiln, for cooling purposes, as described above.

5 The shell 13 of the firing hood carries a plurality of forwardly projecting brackets 60, 61, 62, and 63, each of which comprises a pair of inwardly projecting, spaced apart legs 64 and 65 and a forwardly projecting arm 66, to the forward end of which is pivoted a bell crank lever 67, by a fulcrum pin 68. The two upper bell crank levers each comprise a forwardly projecting horizontal arm 69, having a weight 70 mounted upon its free end, and a downwardly projecting, substantially vertical arm 71, having a rounded head 72 disposed within a socketed seat 73, formed integrally upon the forward face of the flange 27 of ring casting 25. The two lower bell crank levers (Figure 1), each comprises a rearwardly projecting horizontal arm 75, having a weight 76 on its rear end and an upwardly projecting, substantially vertical arm 77, having its upper end similarly disposed in one of the seats 73. Thus, the bell cranks tend to urge the ring casting 25 and the parts carried thereby, rearwardly, toward the firing hood 13, this movement being permitted by the ring supporting wheels 30 and 31 riding upon the tracks 23 and 24. Rearward movement of the 30 non-rotatable ring is restrained by the engagement of the rollers 49 with the forward face of the rotatable ring 44, carried by the kiln shell. As the kiln expands and contracts, axially, the ring casting 25 follows the movements thereof, thereby maintaining the desired seal at all times.

35 The weights 70 and 76, carried by the arms 69 and 75 of the upper and lower bell cranks are mounted thereon for longitudinal adjustment along the arms, to vary the effective force 40 applied by the levers to the nonrotatable ring 53. Under certain conditions, it is desirable to have the rollers 49 so adjusted that the non-rotatable ring 53 and the rotatable ring 44 make sliding, face to face contact, to eliminate the 45 introduction of air into the lower end of the kiln and, in such cases the friction between the rings may be reduced by moving the weights nearer to the fulcrums of the levers and thereby reducing the applied pressure. It will be understood therefore that the introduction of air 50 may be varied from substantially none to the maximum permitted by the eccentricity of the bodies 48 of shafts 47, with the rollers 49 projected the maximum amount, through the slots 55 in the non-rotatable ring 53.

56 Each of the eccentric shafts 48 carries on its radially outer end 47 a lubricant fitting 80, by which lubricant may be delivered, through internal passages, not shown, to the bearing for the roller 49. Each fitting 80 is in communication with one of the conduits 81—89, leading to a bracket 90, carried by the flange 27 of the ring casting 25. The several conduits 81—89 are connected at this point to flexible hoses 91—99, connected at their other ends to a header block 100 and by suitable means to a source of lubricant. Thus, lubricant may be delivered from time to time, or continuously, to the several rollers 49, while the apparatus is in operation, yet the ring casting 25 is free to move axially upon expansion and contraction of the kiln.

60 It should be understood that the above described lubricating system is not an essential of the invention, as sealed bearings for the rollers

may be employed and the conduits and fittings eliminated.

Although the invention has been described with considerable particularity in the foregoing specification, it must be understood that the invention is not limited to the details of construction shown in the accompanying drawings and described above, but includes all modifications coming within the scope of the appended claims and their equivalents.

I claim:

1. A sealing connection for the end of a rotary cylindrical kiln and an adjacent, stationary casing having a circular collar mounted thereon in gas-tight relation and into which said end projects, said connection comprising a non-rotatable ring relatively closely encircling said end of the kiln in spaced relation to said collar and said end and having a substantially radially disposed sealing surface, means supporting the ring from the casing for limited axial movement with respect to the collar, but restraining the ring against rotation, a flexible gas-tight seal between said ring and said collar, a second ring having a substantially radially disposed sealing surface facing said surface of the first ring and disposed in substantially gas-tight sealing relation with respect thereto, said second ring encircling said end of the kiln and secured in gas-tight relation thereto for rotation therewith, means for urging the first ring axially toward the second, to maintain the substantially gas-tight sealing relation between the two, and a plurality of radially disposed rollers carried by the first ring making rolling contact with the adjacent surface of the second ring.

2. A sealing connection for the discharge end of a rotary, cylindrical kiln and an adjacent, normally stationary firing hood having an opening bounded by a circular collar into which said end of the kiln projects, comprising a non-rotatable ring encircling said end of the kiln and supported by the hood in forwardly spaced relation to said collar for limited axial movement with respect thereto and having a substantially radially disposed sealing surface, a flexible gas-tight seal between said ring and said collar, a second ring having a substantially radially disposed sealing surface facing said surface of the first ring and disposed in substantially gas-tight sealing relation with respect thereto, said second ring encircling said end of the kiln and rigidly secured in gas-tight relation thereto in the space between the collar and the first mentioned ring for rotation with the kiln, means for urging the first ring toward the second, and a plurality of circumferentially spaced, radially journaled rollers carried by the first ring, making rolling contact with the adjacent surface of the second ring.

3. An apparatus in accordance with claim 2 in which the means for urging the first ring toward the second comprises a plurality of brackets carried by the hood, projecting forwardly beyond the first ring, a bell crank pivoted to the forward end of each bracket having a substantially vertical arm bearing against the forward face of the first ring and a horizontally extending, weighted arm urging the first mentioned arm in a direction to urge the ring against the second ring.

4. An apparatus in accordance with claim 2 in which the sealing means between the first mentioned ring and the hood comprises an outwardly projecting, flexible annular strip having its inner margin operatively secured to the hood in gas-tight relation, an inwardly projecting flexible annular strip having its outer margin secured

to the outer margin of the first mentioned strip and its inner margin secured to said non-rotatable ring, whereby the ring may move axially relative to the hood by flexing of said annular strips.

5. A sealing connection for the discharge end of a rotary cylindrical kiln and an adjacent normally stationary firing hood of the type having a stationary circular opening into which said end of the kiln projects, said connection comprising a collar surrounding said hood opening and projecting forwardly therefrom, a non-rotatable ring member supported by the hood for limited axial movement with respect thereto, said ring member having a radial flange encircling the lower end of the kiln with its inner margin in spaced relation thereto and a cylindrical, rearwardly projecting flange disposed in concentric spaced relation to said collar, a flexible seal between the collar and said cylindrical flange, a second ring encircling said end of the kiln and rigidly secured thereto in gas-tight relation for rotation therewith, said ring being disposed between the radial flange of the first mentioned ring member and the collar, a plurality of radially journaled rollers carried by the radial flange of said ring member, making rolling contact with the second ring, and means for urging the ring member rearwardly toward the second ring.

6. A sealing connection for the discharge end of a rotary cylindrical kiln and an adjacent normally stationary firing hood of the type having a stationary circular opening into which said end of the kiln projects, said connection comprising a collar surrounding said hood opening and projecting forwardly therefrom, a non-rotatable ring member supported by the hood for limited axial movement with respect thereto, said ring member having a radial flange encircling the lower end of the kiln with its inner margin in spaced relation thereto and a cylindrical, rearwardly projecting flange disposed in concentric spaced relation to said collar, a flexible seal between the collar and said cylindrical flange, comprising a pair of annular strips of gas impervious, flexible material secured together at their outer margins in angular relation and secured at their inner margins, respectively, to said collar and to the cylindrical flange of said ring member, a second ring encircling said end of the kiln and rigidly secured thereto in gas-tight relation for rotation therewith, said second ring being disposed between the radial flange of the first mentioned ring member and the collar, a plurality of radially journaled rollers carried by the radial flange of said ring member, making rolling contact with the second ring, and means for urging the ring member rearwardly toward the second ring.

7. A sealing connection for the discharge end of a rotary cylindrical kiln and an adjacent normally stationary firing hood of the type having a circular opening into which the end of the kiln projects, said connection comprising a collar surrounding the hood opening and having a forwardly projecting cylindrical flange, a ring member supported by the hood forwardly of the collar for limited axial movement with respect thereto but restrained against rotation, said member comprising a cylindrical flange encircling the flange of the collar in concentric, spaced relation thereto, and a radially inwardly projecting flange at the forward end thereof, a flexible gas-tight seal between said cylindrical flanges, a radially outwardly projecting ring encircling said kiln and rigidly secured in gas-tight relation thereto for rotation therewith, said ring

being positioned between the collar and the radial flange of said ring member and facing the latter, means urging the ring member toward the rotatable ring, and a plurality of axially adjustable radially journalled rollers carried by the radial flange of the ring member, making rolling contact with the rotatable ring, whereby the space between the rotatable and non-rotatable elements may be varied by axial adjustment of said rollers.

8. A construction in accordance with claim 7 in which the radial flange of the ring member is slotted at circumferentially spaced points, in which the journals for the roller are carried by the forward face of the flange and in which the rollers project through said slots for engagement with the rotatable ring.

9. A sealing connection for the end of a rotary cylindrical kiln and an adjacent normally stationary casing into which the kiln projects, comprising a non-rotatable ring encircling said end of the kiln, supported by the hood in spaced relation thereto for limited axial movement with respect thereto, a gas-tight seal between the ring and the casing, a second rotatable ring projecting outwardly from the kiln in gas-tight relation thereto and disposed between the first ring and the casing, means for urging the first ring toward the second ring, a plurality of circumferentially spaced, radially journalled rollers, carried by the first ring making rolling contact with the second ring, and conduit means including flexible sections for delivering lubricant from a fixed, external source to each of said rollers.

10. A sealing connection for the discharge end of a rotary cylindrical kiln and an adjacent normally stationary firing hood, comprising a non-rotatable ring encircling said end of the kiln,

supported by the hood in forwardly spaced relation thereto for limited axial movement with respect thereto, said ring having a plurality of circumferentially spaced slots therein, a gas-tight seal between the ring and the hood, a second ring fixed to the kiln, projecting radially outwardly therefrom in gas-tight relation thereto and disposed between the first mentioned ring and the hood, means for urging the first mentioned ring rearwardly toward the second, a plurality of circumferentially spaced, radially journalled rollers carried by the forward face of the first ring, extending through the slots therein and making rolling contact with the second ring, and conduit means including flexible sections for delivering lubricant from a fixed external source to each of said rollers.
